UNITED STATES PATENT OFFICE.

JOHAN MARIUS JOHANSEN, OF TRONDHJEM, NORWAY.

APPARATUS FOR TIGHTENING LEAKAGES IN AND ABOUT BOILER-TUBES AND THE LIKE.

1,395,186.

Specification of Letters Patent. Patented Oct. 25, 1921.

Application filed January 12, 1920. Serial No. 350,774.

To all whom it may concern:

Be it known that I, JOHAN MARIUS JOHANSEN, a subject of the King of Norway, residing at Trondhjem, Norway, have 5 invented certain new and useful Improvements in Apparatus for Tightening Leakages in and About Boiler-Tubes and the like; and I do hereby declare the following to be a full, clear, and exact description of the invention, such as will enable others skilled in the art to which it appertains to make and use the same, reference being had to the accompanying drawings, and to letters or figures of reference marked thereon, which 10 15 form a part of this specification.

The present invention has for its object to provide a device for mending leakages in and about boiler tubes, etc., and comprises a tightening plug consisting of two parts 20 hinged together, said tightening plug, when the parts are put together, fitting tightly into or about the opening of the boiler tube. One part of said tightening plug is pivotally mounted at the front end of a bar adapted 25 to be pushed through the boiler tube, and the other half of the plug is hinged to the said first half at its circumference so as to swing about an axis of the plug.

In the accompanying drawings, 30 Figure 1 is an axial section through the boiler tube with the tightening apparatus inside the same.

Fig. 2 is an axial section through the end of a boiler tube with the tightening apparatus pushed farther forward so that the tightening plug is free outside the tube.

Fig. 3 is a similar section illustrating the apparatus in position for tightening.

Fig. 4 is a cross-section through a tube 40 seen in the direction of the plug which is turned 90° from the position indicated on Fig. 2.

Fig. 5 illustrates a modified form of the invention.

The plug shown in Figs. 1 to 4 consists 45 of two parts A, A' each having the form of substantially a quadrant of a sphere, the two parts being connected together by a hinge P so that they may be folded together 50 to form substantially a semi-spherical body. The plane opposing face of each part is cut away at a to form a recess to receive one end of a rod C. This rod is adapted to extend through a boiler tube as K and the part A 55 of the plug is pivotally mounted on a trun-

nion E, two of which are formed on one end of said rod and extend at right angles to the axis thereof.

The two parts A, A' when being introduced into a tube K, extend along one side 60 of the rod C as shown in Fig. 1, and when said parts pass through the end of the tube they swing into the position shown in Fig. 2 aided by the action of a spring I connected at opposite ends to the rod C and 65 the part A. Further, swinging of the parts by the action of the spring is arrested by a shoulder S on the rod engaging an offset on the part A.

By rotating the rod C counter clockwise 70 180° i. e. in the direction of the arrows G (Figs. 2 and 4) the plane face of part A' of the plug will fold against the plane face of part A and form a substantially semi-spherical plug as shown in Fig. 4.

The part A' has a cylindrical recess a' into 75 which the second trunion E extends when the parts are folded together. Both parts have a beveled flange B adapted to fit around the end of the tube as shown in Fig. 3. In 80 this position the plug tightens the end of the boiler tube, and bar C is kept in position by means of nut and thread (not shown) on its opposite free end. Near the front end the bar C is provided with a bracket L for 85 keeping it approximately in the center of the boiler tube. A projecting rib N is provided on the part A of the plug for keeping the plug members in position relatively to each other. The surfaces M along which 90 the two plug halves are in touch with each other, are provided with a layer of cement or the like for keeping the connection tight.

In the modification of the invention illustrated on Fig. 5 the spring I and the collar 95 B are left out. The tightening plug is conical and in its assembled position fits into the tube with its narrow end. When bar C is drawn into the tube, the conical plug is caused to exert an outwardly directed pressure on the tube end, whereby the connection between the same and the boiler plate is tightened, and at the same time the tube end is tightened in case there should be a leakage somewhere on the tube. The apparatus is introduced through the position indicated in dotted lines, and after having been pushed entirely through the tube, the bar is rotated, whereby the outward half of the plug is pivoted on its hinge and is 100 105 110

brought together with the innermost plug half. In order to secure correct position of the plug halves with regard to the bar C, the outward half of the plug is provided 5 with a recess adapted to fit about the front end of bar C and the projecting end of trunnion E.

Claims:—

1. In an apparatus for tightening leakages and the like, a tightening plug, consisting of two halves, one half of the tightening plug being pivotally mounted at the front end of a bar, adapted to be introduced through a boiler tube, while the other half 10 of the plug is hinged at its circumference to the first mentioned half of the plug.
2. In an apparatus for tightening leakages and the like a conical tightening plug, consisting of two halves, one half of the tightening plug being pivotally mounted at 15 the front end of a bar, adapted to be intro-

duced through a boiler tube, while the other half of the plug is hinged at its circumference to the first mentioned half of the plug.

3. In an apparatus for tightening leakages and the like a tightening plug, consisting of two halves, one half of the tightening plug being pivotally mounted at the front end of a bar, adapted to be introduced through a boiler tube, while the other half 25 of the plug is hinged at its circumference to the first mentioned half of the plug, the plug being provided with a collar or flange 30 adapted to fit round the end-opening of a boiler tube.

In testimony that I claim the foregoing as my invention, I have signed my name in presence of two subscribing witnesses.

JOHAN MARIUS JOHANSEN.
